UNITED STATES PATENT OFFICE

2,609,619

RAILROAD TRACK SKELETONIZING
MACHINE

Harry C. Jones, Magnolia, Ark.

Application August 9, 1946, Serial No. 689,416

3 Claims. (Cl. 37—104)

1

My invention relates to railroad track work and more particularly to a machine for skeletonizing railroad tracks.

The object of my invention is to provide a machine adapted to remove the old ballast from a railroad track bed, when it is desired to put new ballast on said track bed.

Another object of my invention is to provide a machine adapted to lift and support a railroad track, that means the rails together with the ties, to which said rails are fastened, while the machine removes the old ballast from the road bed.

Other objects of my invention may appear in the following specification describing my invention with reference to the accompanying drawings illustrating a preferred embodiment thereof. It is, however, to be understood that my invention is not to be limited and restricted to the exact construction and combination described in the specification and shown in the drawings, but that such changes and modifications can be made which fall within the scope of the claims appended hereto.

In the drawings:

Fig. 1 is a side elevational view of a machine according to my invention in working position over a railroad track, some parts being shown as broken away and in section.

Fig. 2 is a top plan view of Fig. 1, parts of the wheels being broken away.

Fig. 3 is a sectional view taken on line 3—3 in Fig. 2.

Fig. 4 is a sectional view taken on line 4—4 in Fig. 3, shown in a bigger scale.

Fig. 5 is a sectional detail view in a larger scale showing the construction of the front wheels, the front axle and a part of the steering mechanism.

Fig. 6 is a sectional view taken on line 6—6 in Fig. 5.

Fig. 7 is a sectional detail view taken diametrically through the rear axle and showing the construction of the brake mechanism.

Fig. 8 is a front view of Fig. 7.

Fig. 9 is a sectional view taken on line 9—9 in Fig. 1.

Fig. 10 is a detail view showing a part of the gear shifting mechanism.

Fig. 11 is a detail side elevation of the rail supporting mechanism.

Fig. 12 is a sectional view taken on line 12—12 in Fig. 11.

Fig. 13 is a sectional view taken on line 13—13 in Fig. 11.

Fig. 14 is a detail view, partly shown in section,

2

of the latch mechanism for the roller arms used in connection with my invention.

Referring now in detail to the drawings, the railroad track skeletonizing machine according to my invention has a platform 15. On the rear portion of the platform there is a motor, not shown, which is covered by a motor hood 17. The platform 15 is supported by four wheels, two rear wheels 18 and two front wheels 19.

10 A rear axle 20 extends transversely underneath the rear portion of the platform 15 and is rotatably fastened thereto. This rear axle extends far enough beyond both longitudinal edges of the platform to reach over the rails of a railroad track.

The front and rear wheels are constructed substantially similar to each other.

Each wheel consists of a central wheel 21 constructed to travel on a rail 22 and equipped with a circular flange 23 like a conventional railroad wheel, and an outer wheel 24. The outer wheel has a hub 25, from which a plurality of spokes 26 extend radially and outwardly. The rim of the outer wheel is either formed integrally with the hub and the spokes or securely fastened onto the latter. The bore in the hub 25 of the outer wheel is shaped so that it fits snugly onto the rim of the center wheel 21 as shown in Fig. 5. This rim and the hub 25 are securely held together by means of a plurality of bolts 27. The rear wheels 18 are secured to the rear axle 20 so that they rotate with the axle. The axle 20, however, is provided with a flattened surface 28 adjacent each of its ends and a plurality of holes 29.

30 When the machine is in use the outer wheels 24 are attached to the center wheels 21 and the assembled wheels 18 are fastened on the outer ends of the rear axle 20 as shown in Fig. 2 so that the wheels are located outside of the ends of the ties 30 of the track. When the machine is out of use and is to be transported to a new working place the outer wheels 24 are removed from the center wheels 21 and the latter are moved inwardly on the rear axle 20 and fastened again thereon so that the center wheels will travel on the rails 22.

The front wheels 19 are, as stated above, constructed like the rear wheels 18; they are, however, rotatably mounted on the front axle 31 and are held in adjusted position by rings 32 fastened onto the front axles by means of bolts 33. The front axles 31 are provided with tapped holes 34 so that the front wheels 19 can be positioned on these axles to correspond with the rear wheels 18.

40 Adjacent each longitudinal edge of the plat-

50 form 15 are detail side elevations of the rail supporting mechanism. The front wheels 19 are, as stated above, constructed like the rear wheels 18; they are, however, rotatably mounted on the front axle 31 and are held in adjusted position by rings 32 fastened onto the front axles by means of bolts 33. The front axles 31 are provided with tapped holes 34 so that the front wheels 19 can be positioned on these axles to correspond with the rear wheels 18.

55 Adjacent each longitudinal edge of the plat-

form 15 a sprocket gear 35 is rigidly mounted on the rear axle 20.

On the motor shaft 36 a bevel gear 37 is rigidly mounted forming the driving gear for the entire mechanism.

For driving the machine forward at three different speeds or in reverse a gear shift mechanism is arranged. The shift gears are located inside the motor hood and are shown best in Fig. 9.

The bevel gear 37 on motor shaft 36 meshes with two other bevel gears 38 and 39 respectively. The bevel gear 38 is rigidly mounted on a shaft 40 rotatably mounted in a bearing 41 and a triple bearing 42. On the outer end of shaft 40 a gear 43 is rigidly mounted and meshes with two other gears 44 and 45 respectively. Each of these two gears is mounted on a clutch shaft 46 and 47 respectively, rotatably supported by the triple bearing 42 and a second triple bearing 48. On the clutch shaft 46 a clutch 49 and a gear 50 is mounted and on the clutch shaft 47 a gear 51 and a clutch 52 is arranged. The two gears 50 and 51 mesh with a gear 53 arranged between them and rigidly mounted on a shaft 54 rotatably supported by the triple bearing 48 and a bearing 55. The shaft 54 extends outwardly of the motor hood 17 and on its outer end a sprocket gear 56 is rigidly mounted and arranged in alignment with the corresponding sprocket gear 35 on the rear axle 20. A sprocket chain 57 is trained over these two sprocket gears. A shift lever 58 connects the two shift clutches 49 and 52 and is pivotally supported between them as shown at 59. This shift lever 58 is connected to a shifting rod 60 by means of a link lever 61.

The second bevel gear 39 meshing with the main driving bevel gear 37 is rigidly mounted on a clutch shaft 62 supported in two double bearings 63 and 64 and a triple bearing 65. A gear 66 is rigidly mounted on the clutch shaft 62 between the bevel gear 39 and the double bearing 63 and meshes with a second gear 67 rigidly mounted on a second clutch shaft 68 rotatably supported in the two double bearings 63 and 64 and the triple bearing 65. Two clutch members 69 and 70 are slidably but not rotatably mounted on the clutch shafts 62 and 68 respectively and corresponding clutch members 71 and 72, rigidly connected with gears 73 and 74 respectively, are rotatably but not slidably mounted on the clutch shafts 62 and 68 respectively. A gear 75 arranged between and meshing with the gears 73 and 74 is rigidly mounted on a shaft 76 which is rotatably supported by the triple bearing 65 and a bearing 77. This shaft 76 extends outside of the motor hood 17 and on its outer end a sprocket gear 78 is rigidly mounted and arranged in alignment with the corresponding sprocket gear 35 on the rear axle 20. A sprocket chain 79 is trained over the sprocket gears 78 and 35. A shifting lever 80 connects the clutch members 69 and 70 and is pivotally supported between the two members as indicated at 81.

A link lever 82 connects the shift lever 80 with a shift rod 83.

Forwardly of the motor hood 17 a combined seat and tool box 84 is arranged on top of the platform 15 and extends transversely thereof.

A gear shift lever 85 is arranged in front of the driver's seat 84 in easy reach of the driver and is movable in a guide frame 86 having an H-shaped guide way 87 therein. The forward ends of the shifting rods 60 and 83 pass through the guide frame 86. Each of the shifting rods 60

and 83 has a square notch 88 and 89 respectively in its inner surface adjacent its forward end.

When the gear shift lever 85 is set in the cross passage of the H-shaped guide way 87 the notches 88 and 89 are located coinciding with this cross passage. The shift clutches are arranged as shown in Fig. 9, that means they are in neutral or non-driving position. When the gear shift lever 85 is moved to the right in Fig. 10 it engages the notch 89 in the shifting rod 83. If the lever 85 is then pulled backward the rod 83 will also be moved toward the rear and will engage the shift clutch 70-72 so that the sprocket gear 78 will be driven by the gears 67, 74 and 75 driving the machine in reverse direction. By moving lever 85 to the right and forward, clutch 69-71 will be engaged and the sprocket gear 78 will be driven by the gears 66, 73 and 75 so that the machine will be driven forwardly at 1st speed. When the gear shift lever 85 is moved to the cross passage and then to the left, it will engage the notch 88 in the shifting rod 60. By moving the lever 85 backward the clutch-members 52 will be engaged with each other so that the machine will be driven forwardly at 2nd speed by the gears 43, 45, 51, 53, and the sprocket gear 78. If the gear shift lever 85 is then moved all the way forward clutch-members 52 will be disconnected and clutch-members 49 will be engaged with each other, so that the machine is driven at 3rd speed forward by the gears 43, 44, 50, 53 and sprocket 56.

A brake pedal 90^a is arranged also in front of the driver's seat and in easy reach of the driver. A brake rod 90 is linked with this pedal and extends rearwardly therefrom. Intermediate the ends of the rear axle 20 two substantially semi-circular brake members 91 are arranged. They surround the rear axle and are hingedly connected with each at their bottom edges as shown at 92 in Figs. 7 and 8. Each brake member has on its upper edge at its longitudinal center a pair of lugs 93 with concentrical holes therein. There is a longitudinal cut out 94 provided in the platform 15 and a bracket 95 is fastened therein serving as a guide for the brake rod 90. Two lever arms 96 and 97 respectively are pivotally fastened intermediate their ends onto the platform 15 as shown at 98 in Fig. 8 so that they cross each other. The lever arm 96 has a slot in its upper portion and a pin 99 on the end of the brake rod 90 extends through this slot. The lower end of the cross lever arm 96 is located between the lugs 93 on the forward brake member 91 and is pivotally connected with them. The lower end of the cross lever arm 97 is arranged between the lugs 93 on the rear brake member 91 and is pivotally connected with them. On its upper end this lever arm 97 has guide ring 100 with a slot 101 therein. The brake rod 90 extends through this slot and the ring abuts the bracket 95. When the brake pedal 90^a is actuated the brake lever 90 is moved forwardly acting on the two cross lever arms 96 and 97 to force the brake members against the rear axle 20 and to exert a brake pressure thereon.

A steering column 102 extends upwardly from a gear box 103 fastened on top of the platform 15 in front of the driver's seat 84. A steering shaft 104 extends through the steering column 102 and is rotatably supported therein. It extends beyond the top of the steering column and a steering wheel 105 is fastened on the top end of the steering shaft 104. On the lower end of said steering shaft a gear 106 is rigidly mounted inside the gear box 103. Another gear 107 meshes

with the gear 106 and is rigidly mounted on a stub shaft 108 extending through and rotatably supported in the platform 15. On the lower end of the stub shaft 108 another gear 109 is rigidly mounted.

On the inside end of the front axle 31 a horizontally arranged hub 110 is formed from which two spokes 111 extend radially and inwardly.

These spokes carry on their outer ends toothed arcuate rims 112 each of which forms approximately one sixth of a gear meshing with the last named gear 109. From each horizontal hub 110 a pivot shaft 113 extends upwardly into the platform 15 where it is rotatably supported. Arcuate support brackets 114 are located underneath the gear segments 112 and fastened to the under side of the platform 15. On the rim portion of the gear segments 112 a plurality of downwardly extending lugs 115 are arranged in pairs, which rotatably support rollers 116 adapted to roll on the supports 114 when the steering wheel 105 is actuated and pivots the front axles 31 about the pivot shafts 113 by means of the gears 106, 107, shaft 108, gear 109 and gear segments 112.

When the machine is in use to remove old ballast from a railroad bed, the machine lifts the assembled rails and ties to facilitate the work. The rail lifting mechanism is supported by two hangers 116 which are removably attached to the platform 15.

Each hanger 116 has a horizontal base plate 117 extending longitudinally relative to the machine. On each end of the base plate 117 an outwardly and upwardly sloping end arm 118 is integrally formed with said base plate. In the center of the base plate a hole is provided to permit a bolt 119 to extend therethrough for a purpose to be described later.

Adjacent to this hole two other arms 120 extend outwardly and upwardly from the base plate and unite with the adjacent arm 118 as shown at 121 in Fig. 1.

On each side of the platform 15 a pair of brackets 122 is arranged and extends at the same angles as the end arms 118 so that a hanger 116 can be placed on and between a pair of brackets 122. Each hanger 116 is secured in position by bolts 123 extending through key holes provided in the brackets and in the end arms for quick removal of said hangers.

On each end of the base plate 117 two roller housings 124 are formed on the under side of said plate and extend transversely thereof. On the bolt 119 four levers are pivotally mounted. Each lever has a guard lever arm 125 and a roller lever arm 126. The two arms of each lever are connected with each other by a hub 127 and spacer tube 128 surrounding the bolt 119 is arranged between the base plate 117 and the uppermost hub 127.

There are four supports 128 suspended by rollers 129, which are slidably located in the roller housings 124. Each support has two upwardly extending prongs 130 through which a stub-shaft 131 extends. The prongs are arranged slidably on the longitudinal sides of the roller housings and the stub shafts extend through the rollers in said housings, and said housings are shaped arcuate about the axis of the bolt 119. Each roller arm 126 is firmly attached to or integrally formed with the adjacent support 128. A knuckle 132 has an upwardly extending shaft 132a which is rotatably but not slidably arranged in the support 128. The inner surface of each knuckle 132 is finished and a clamp roller 133 is rotat-

ably mounted thereon as best shown in Fig. 12. The roller 133 is hollow and forms with its inner surface the outer race of a conical roller bearing 134 which is attached to the knuckle 132 by means of a bolt 135.

Onto the end of each guard lever arm 125 a connecting link 136 is pivotally attached and connects said guard lever arm with a guard arm 137 to which it is pivotally linked. The guards 10 surround the clamp rollers 133 as indicated at 138, in Figure 13 and are pivotally connected with the supports 128.

When the machine is in use one set of clamp rollers, for instance the forward set, is engaging the rail 22 underneath its head as indicated in Figure 13, holding the rails 22 and ties 30 in lifted position. While the machine moves forward the forward clamp rollers roll under the rail heads lifting the track. The forward guards are positioned as shown in Figure 13 protecting the clamp rollers. The rear guards and clamp rollers are swung outwardly as shown in Figure 13. When the forward guard 137 comes in contact with a connecting plate 22a between two abutting rails the guard slides onto this plate pivoting on its connection with the support 128. The link 136 transmits this movement to the guard lever arm 125 swinging it outwardly about the bolt 119. The rear roller lever arm 126 on the guard lever arm is swung inwardly so that the rear roller engages the rail. The adjacent guard is also moved inwardly pivoting the rear guard lever arm inwardly and the forward roller lever arm outwardly, so that now the forward clamp rollers and guards are disengaged from the rail and corresponding rear clamp rollers and guards are engaging and supporting the rail. When these guards and rollers come in contact with a connecting plate 22a they will be disengaged from the rail pivoting the front clamp roller and guard again into working position.

To prevent the above described mechanism from acting too soon and releasing the supported rail a lock mechanism is provided.

On one roller arm 126 of the two front roller arms and of the two rear roller arms an inwardly extending curved lock arm 182 is formed adjacent the corresponding support 128. On top of each lock arm 182 a pair of lugs 183 is arranged supporting a crank lever 184 rotatably between them. A control bar 185 is pivotally connected at one of its ends with one arm of the crank lever 184 and at the other end with the adjacent guard lever arm 125. To the other arm of the crank lever a latch 186 is pivotally attached and extends downwardly through a guide hole provided in the lock arm 182. The latch 186 has a neck 188 surrounded by a spring 189 abutting the latch proper and permitting it to slide upwardly on said neck.

A latch receiving arm 187 is formed on the other arm of each front and rear pair of roller arms 126 and extends inwardly underneath the lock arm 182. A hole is provided in this latch receiving arm and is adapted to be engaged by the latch 186. When the guard arm is pivoted outwardly the latch is lifted out of the latch receiving arm, and when the guard arm is swung inwardly the latch 186 is lowered to engage the hole in the latch receiving arm.

Adjacent its forward end the platform 15 has two laterally projecting portions 139. As best seen in Figure 2 these lateral projections extend beyond the ends of the ties 30.

A shaft 140 extends transversely of the plat- 75 form 15 centrally of the projections 139 and is

rotatably supported by bearings 141 on the platform 15.

A shaft 142 is connected firmly with or formed integrally with the motor shaft 36, and is rotatably supported by a bearing 143 on the platform 15. This shaft extends forwardly into the seat 84 and a clutch member 144 is rigidly mounted on its end. Another shaft 145 is rotatably supported on the platform 15 by bearings 146 and is arranged coaxially with the shaft 142. On its rear end, which extends into the seat 84 the shaft 145 is equipped with a clutch member 147, which is slidably but not rotatably mounted on the shaft 145. A clutch lever 148 located in front of the driver's seat 84 is connected by a link 149 to a ring 150 surrounding the clutch member 147 so that the latter can be slid into engagement with the clutch member 144 to rotate the shaft 145. A bevel gear 151 on the forward end of this shaft meshes with another bevel gear 152 rigidly mounted on the transverse shaft 140.

A pair of endless diggers arranged in end to end spaced and partially overlapped relation is positioned below the platform 15 adjacent to the front end thereof and each of such diggers is mounted for rotation about a vertical axis, the diggers engaging the railway ballast underneath the lifted track, each digger has a block 153 the sides whereof taper inwardly. Each end is open to receive a neck or stem of a double sprocket gear 154. A plug 155 is adapted to close the open end and is held in position by screws 156. The outside double sprocket gears are bigger than the inner gears 157 which are arranged in the same manner as the outer and bigger gears. The teeth of the sprocket gears extend beyond the outline of the block, so that the double sprocket chains 158 travel about the block at levels somewhat below the top and somewhat above the bottom surface thereof. The sprocket chains 158 on each block 153 carry between them an endless digger embodying a conveyor belt 159 having outwardly extending diggers 160 thereon adapted to excavate the ballast on the road bed.

Each block 153 has in its upper surface two tapped holes 161 located on the longitudinal center line of the block. A heavy metal plate 162 has four holes therein permitting bolts 163 to extend therethrough and engage the tapped holes 161 so that the diggers are arranged with their smaller forward ends extended a little beyond each other as indicated in Fig. 4. On the rear edge of the metal plate 162 three rearwardly projecting tangs 164 are arranged which have downwardly bent rear ends serving as brackets for two laterally and rearwardly extending scraper blades 165. As shown in Fig. 1 these blades are arranged also at an angle to the road bed.

Adjacent each of its outer side edges the metal plate 162 has an upwardly extending sleeve 166 provided with a thread on its outer circumference. Two corresponding sleeves 167 are arranged on the platform 15 extending downwardly therefrom. A hole extends through the platform concentrically with each sleeve 167. Two circular casings 168 are provided at both of their ends with female threads adapted to engage the threads on the sleeves 166 and 167 firmly but removably attaching the diggers to the machine. The double sprocket gears 154 have each a centrally located square depression 169 in their top and a shaft 170, extending through the casing 168, the two sleeves 166 and 167, and the hole in the platform above the last named sleeve, has a square offset portion 171 on each of its ends. The lower of these portions engages the square depression 169.

and the shaft rests on the top of the double sprocket gear.

A bevel gear 172 is arranged on top of each lateral projection 139 of the platform and has a square center hole therein, adapted to receive the top square portion 171 of the shaft 170 therein.

On each end of the transverse shaft 140 a bevel gear 173 is rigidly mounted and meshes with the corresponding bevel gear 172.

When the motor 16 is running and the clutch members 144 and 147 on the longitudinal shafts 142 and 145 respectively are engaged, the conveyor belts are driven to circulate in opposite directions engaging and removing the ballast under the lifted track outwardly. Since the inner ends of the two diggers overlap each other the whole area underneath the track is worked. Any stray ballast eventually missed by the diggers is removed by the scraper blades 165 following the diggers.

To facilitate the work of the diggers a pair of spreaders 174 is provided and securely but easily removably attached onto the lateral projections 139 of the platform 15.

Each spreader has a scraper blade 175 on a stem 176 with laterally extending lugs 177 thereon adjacent its upper end.

A recess 178 is provided in the front surface of each of the lateral projections 139 and each recess has lateral extensions 179. The upper end of the scraper stems 176 fit into the recesses 178 and the lugs 177 secure the scrapers 174 in position by engaging the recess extensions 179. On each casing 168 and on each spreader stem 176 an eye 180 is provided so that the corresponding eyes are located opposite to each other, and a double hook 181 is adapted to engage the two opposite eyes, thereby stiffening the spreader stems 176.

The above description shows clearly the construction and the method of working of the skeletonizing machine according to my invention, and it is also easily understood therefrom that all the parts connected therewith which engage, lift and hold the track or which are working the road bed underneath and about said track are easily and quickly detachable from said machine.

Having described my invention I claim as new and desire to secure by Letters Patent:

1. In an apparatus for removing railway ballast, a wheel supported platform adapted for straddling travel over a track supported on said ballast, a pair of horizontally disposed endless diggers arranged in end to end spaced and partially overlapped relation positioned transversely of said track and below said platform adjacent the front end thereof and each mounted for rotation about a vertical axis for excavating the railway ballast adjacent thereto, a pair of upstanding spreaders arranged in spaced converging relation positioned forwardly of and spaced from said endless diggers and dependingly supported from said platform, and driving mechanism on said platform and operatively connected to each of said axes for effecting rotation of said endless diggers.

2. In an apparatus for removing railway ballast, a wheel supported platform adapted for straddling travel over a track supported on said ballast, a pair of horizontally disposed endless diggers arranged in end to end spaced and partially overlapped relation positioned transversely of said track and below said platform adjacent the front end thereof and each mounted for rotation about a vertical axis for excavating the

railway ballast adjacent thereto, a pair of upstanding spreaders arranged in spaced converging relation positioned forwardly of and spaced from said endless diggers and dependingly supported from said platform, a pair of upstanding scraper blades arranged in converging spaced relation with respect to each other positioned rearwardly of and spaced from said endless diggers and operatively connected to the latter, and driving mechanism on said platform and operatively connected to each of said axes for effecting rotation of said endless diggers.

3. In an apparatus for removing railway ballast, a wheel supported platform adapted for straddling travel over a track supported on said ballast, a pair of horizontally disposed endless diggers arranged in end to end spaced and partially overlapped relation positioned transversely of said track and below said platform adjacent the front end thereof and each mounted for rotation about a vertical axis for excavating the railway ballast adjacent thereto, a pair of upstanding spreaders arranged in spaced converging relation positioned forwardly of and spaced from said endless diggers and dependingly supported from said platform, a horizontally disposed plate superimposed upon said endless diggers and dependingly supported from said plat-

form, a pair of upstanding scraper blades arranged in converging spaced relation with respect to each other positioned rearwardly of and spaced from said endless diggers and connected to said plate, and driving mechanism on said platform and operatively connected to each of said axes for effecting rotation of said endless diggers.
